US0D1076771S

(12) **United States Design Patent** (10) **Patent No.:** **US D1,076,771 S**
(45) **Date of Patent:** **** May 27, 2025**

(54) **TRAY**

(71) Applicant: **Guangzhou Songxianjun Trading Co., Ltd.**, Guangzhou (CN)

(72) Inventor: **Jiakai Chen**, Jieyang (CN)

(73) Assignee: **Guangzhou Songxianjun Trading Co., Ltd.**, Guangzhou (CN)

(**) Term: **15 Years**

(21) Appl. No.: **29/968,266**

(22) Filed: **Oct. 15, 2024**

(51) LOC (15) Cl. **12-16**

(52) U.S. Cl.

USPC **D12/425**

(58) **Field of Classification Search**

USPC D3/313; D6/406.1, 406.2, 406.3, 406.4, D6/406.5, 406.6, 524, 525; D7/549, D7/550.1, 552.1, 552.2, 553.1, 553.2, D7/553.3, 553.4, 553.5, 553.7, 554.1, D7/554.3, 554.4, 555; D12/345, 400, D12/415, 416, 419, 421, 423, 424, 425, D12/426; D19/65, 75, 77, 92, 95, 101, D19/102

(57) **CLAIM**

The ornamental design for tray, as shown and described.

DESCRIPTION

FIG. 1 is a front perspective view of tray, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the tray, which form no part of the claimed design.

1 Claim, 8 Drawing Sheets
